(57) **CLAIM**

The ornamental design for a combined infrared camera and thermal imager, as shown and described.

DESCRIPTION

FIG. 1 is a front and right side perspective view of a combined infrared camera and thermal imager showing my new design; FIG. 2 is a front and right side perspective view with the objective in a retracted position; FIG. 3 is a front elevational view thereof, with the objective in an extended position; FIG. 4 is a front elevational view thereof, with the objective in a retracted position; FIG. 5 is a top plan view thereof, with the objective in an extended position; FIG. 6 is a top plan view thereof, with the objective in a retracted position; FIG. 7 is a bottom plan view thereof, with the objective in an extended position; FIG. 8 is a bottom plan view thereof, with the objective in a retracted position; FIG. 9 is a left side elevational view thereof, with the objective in an extended position; FIG. 10 is a left side elevational view thereof, with the objective in a retracted position; FIG. 11 is a right side elevational view thereof, with the objective in an extended position; FIG. 12 is a right side elevational view thereof, with the objective in a retracted position; and, FIG. 13 is a rear elevational view thereof. The portions of the article in broken lines are shown for illustrative purposes only and form no part of the claimed design.
